UNITED STATES PATENT OFFICE.

KENTON CHICKERING, OF OIL CITY, PENNSYLVANIA.

CASING AND TUBING ELEVATOR.

SPECIFICATION forming part of Letters Patent No. 729,846, dated June 2, 1903.

Application filed February 3, 1902. Serial No. 92,379. (No model.)

To all whom it may concern:

Be it known that I, KENTON CHICKERING, a citizen of the United States, residing at Oil City, in the county of Venango, State of Pennsylvania, have invented certain new and useful Improvements in Casing and Tubing Elevators; and I hereby declare the following to be a full, clear, and exact description of the same, reference being had to the accompanying drawings, in which—

Figure 1 is a perspective view of a casing and tubing elevator embodying my invention, the sections closed as when in use. Fig. 2 is a perspective view thereof, the sections open to receive the tubing or casing. Fig. 3 is a top plan view of the elevator, the sections closed as in Fig. 1. Fig. 4 is a side elevation of the elevator, the sections closed and the pin-latch shown in dotted lines. Fig. 5 is a vertical section on the line 5—5, Fig. 4, to show the vertical taper of the locking-arms.

Like symbols refer to like parts wherever they occur.

My invention relates to that class of devices employed for lowering, raising, or drawing well tubing or casing, commonly termed "casing or tubing elevators," and comprising suitable reins or bail-links, clamp-sections suspended therefrom, and a locking mechanism for the clamp-sections, and has for its objects to so construct and combine the clamp and lock mechanism as to insure the proper closing of the clamp-sections and support the same against forces which tend to strain the pivot and separate the clamp-sections laterally at their lower ends or at points below the bail-links.

To this end my invention, generally stated, embraces the combination, in a casing or tubing elevator and with the pivoted clamp-jaws thereof, of a yoke or link-latch, which includes the locking-arms above and a second lock below the bail-link of the elevator, whereby the clamp-sections are supported against forces which tend to separate them and strain the pivot thereof.

There are other minor novel features of construction, as also combinations of parts, all as will be hereinafter fully set forth and claimed.

I will now proceed to describe my inven-

tion more fully, so that others skilled in the art to which it appertains may apply the same.

In the drawings, 1 and 2 indicate the clamp or jaw sections of the elevator, each provided with a perforated bail-ear or bail-lug *a* for the reception of the usual bail-links or reins *A A*. The clamp or jaw sections 1 and 2 have the usual concave or semicircular tube-seats 60 33, are pivotally connected on one side, as at 4, and opposite thereto are provided with the lugs or locking-arms 5 5^a or equivalent projections for the reception of a yoke or link-latch 6, which serves to lock the clamp-sections together above or at the top. The lugs or locking-arms 5 5^a are of the same general form in so far as both are recessed at their junction with the body of the clamp, as at 1^a 2^a, to form a yoke or latch seat and receive the upper end of the yoke or link-latch 6, which link-latch lies flush with and completes the upper surface of the clamp, and also in so far as both lugs or locking-arms 5 5^a taper 70 slightly from within outward (see Fig. 3) and from below upward, (see Fig. 5,) so that the yoke or link-latch 6 as it is moved into position to close the clamp-jaws forces said lugs or locking-arms 5 5^a into apposition from without inward and from above downward and 75 insures an effective support of the jaws or sections at the bottom of the clamp, where most required to relieve the pivot from undue strain and prevent the separation of the clamp-jaws.

The yoke or link-latch 6 is pivotally secured to the lug or locking-arm 1 by means of a bolt 6^a, (either with or without a sleeve 6^b,) which passes through an elongated slot 5^b, so as to permit sufficient forward play of the yoke or 80 link-latch 6 to insure its proper seating when the jaw-sections 1 and 2 are to be locked by the yoke or link-latch, and the slot or the interior walls of the link-latch converge to correspond with the vertical taper of the locking-arms 5 5^a, (see Figs. 2 and 3,) which arms or lugs the link-latch incloses when the clamp-jaws are locked together.

The lug or locking-arm 5^a is cut back or notched in, as at 5^c, to accommodate the bolt 100 6^a or pivot of the latch 6 and permit the link-latch 6 to be swung outward and free from arm 5^a when the jaw-sections 1 and 2 are to be opened, and said arm 5^a is provided with a

lug or locking-pin 7, which passes through a pin-hole 8 in the opposite arm 5, said locking-pin being provided at its outer end with a circumferential groove 7^a (or button) for the reception of a pin-latch 9, preferably formed on or attached to and projecting downward from the link-latch or yoke 6.

For reasons which will hereinafter appear the locking-pin 7 and pin-latch 9 are the preferred means of locking the jaw-sections together at a point below the bail-links or reins A A; but any equivalent therefor may be substituted, if desired.

The inner faces of the lugs or locking-arms 5 5^a may be slightly hollowed out or recessed, as at 5^b, if desired, to facilitate the separation of the jaws 1 and 2 when releasing the tube or easing from the elevator.

The construction of the elevator being substantially such as hereinbefore pointed out, it will be applied to the tube or easing to be raised or lowered as follows: The link-latch 6 being thrown over and down to release the lug or locking-arm 5^a and the locking-arms 5; separated, (see Fig. 2,) the tubing or easing is introduced between the jaws or sections 1 and 2, the locking-arms 5 5^a brought together, after which the yoke or link-latch 6 is turned up and inward over the locking-arms and its upper end is forced down into the latch-seats 1^a 2^a. In instances where the tubing or easing has a flange-thimble or coupling-sleeve the same may rest on the upper edge or rim of the jaw-sections 1 and 2 and on the yoke or link-latch, and the weight of the tubing will assist in holding the yoke or link-latch firmly on its seat. The link-latch 6 as it is forced forward and inward acts on the vertical and horizontal inclines or tapering parts of the locking-arms, (see Figs. 3 and 5,) so as to force the arms into contact, especially at the bottom of the jaws, and this also causes the locking-pin 7 to pass through the hole 8 in lock-

ing-arm 5, and at the same time, if the pin-latch is affixed to the link-latch 6, the movement of the latch causes the pin-latch 9 to engage the outer end of the locking-pin 7, and thus lock up and support the lower portion of the clamp-jaws and pivot against lateral and torsional strains. 45 50

While the pin-latch is not necessarily affixed to the link-latch or yoke 6, it is preferably joined thereto, as it simplifies the construction, facilitates the locking and unlocking of the elevator-jaws, insures against accidental displacement of the pin-lock, and enables the pin-lock to also assist in drawing together and supporting the locking-arms of the elevator-sections. 55

Having thus described my invention, what I claim, and desire to secure by Letters Patent, is—

1. In a easing or tubing elevator having bail-links, the combination with pivoted clamp-jaws having locking arms or lugs, of a yoke or link-latch which incloses the locking-arms above the bail-links, and a pin-lock and latch therefor, which confine the locking-arms below the bail-links, substantially as and for the purposes specified. 65 70

2. In a easing or tubing elevator, the combination with pivoted clamp-jaws having locking-arms one of which is provided with a pin and the other with a pin-hole, of a yoke or link-latch provided with an arm or pin-lock which engages the pin and forms a lock therewith, substantially as and for the purposes specified. 75

In testimony whereof I affix my signature, in presence of two witnesses, this 1st day of February, 1902.

KENTON CHICKERING.
